US00D732247S

(12) **United States Design Patent** (10) **Patent No.:** **US D732,247 S**
Reid (45) **Date of Patent:** **** Jun. 16, 2015**

(54) **HAY NET FILLER**

- (71) Applicant: **Gary Reid**, Hugo, MN (US)
(72) Inventor: **Gary Reid**, Hugo, MN (US)
(**) Term: **14 Years**
(21) Appl. No.: **29/486,496**
(22) Filed: **Mar. 31, 2014**
(51) LOC (10) Cl. **30-03**
(52) U.S. Cl. **USPC D30/131; D30/121**
(58) **Field of Classification Search**
USPC D30/133, 121, 122, 124, 127, 128, 132, D30/129–131; 119/51.01, 61, 51.04, 53, 119/57.91, 54, 53.5, 52.4, 51.11, 63, 61.2, 119/52.1, 57.5, 57.6, 51.13, 62, 75, 500, 119/501, 73, 74, 51.12, 51.5, 52.2, 61.1, 60, 119/58, 59, 61.4, 65, 68, 69, 791; 239/7, 239/687, 379, 397.5; 222/199, 181.1, 222/181.2, 185.1, 557, 156, 485, 486, 548, 222/555; 220/200, 227, 247, 262, 697–702; 221/174, 185.1, 289, 295, 296, 559; 454/35; 209/270, 283, 244; 52/194, 52/192; 49/279, 344, 357; D34/28, 5, 6; D7/409, 601; 211/181.1, 85.3, 211/195–200; 414/24.5; D32/53.1, 35–39, D32/58, 60, 73; 15/260, 262, 264, 257.01, 15/257.05, 257.06; 118/419; D9/424, 429; D11/156, 143–155, 64; D6/403, 678.4; 248/95–105, 127, 136, 166, 434, 439, 248/440, 176.1, 150, 436; 280/79, 98

Primary Examiner — Susan Moon Lee

(74) Attorney, Agent, or Firm — Geiser Law, PLLC

(57) **CLAIM**

The ornamental design for a hay net filler, as shown and described.

DESCRIPTION

FIG. 1 is a perspective view of a hay net filler showing my new design;

FIG. 2 is a rear elevational view thereof; and,

FIG. 3 is a right side elevational view thereof, the left side being a mirror image.

The broken lines shown in the figures are for environmental purposes only and form no part of the claimed design.

1 Claim, 2 Drawing Sheets
